UNITED STATES PATENT OFFICE.

FRANK H. WILLIAMS, OF BUFFALO, NEW YORK.

GRAB-BUCKET.

1,329,868.

Specification of Letters Patent.

Patented Feb. 3, 1920.

Application filed June 18, 1918. Serial No. 240,615.

To all whom it may concern:

Be it known that I, FRANK H. WILLIAMS, a citizen of the United States of America, and a resident of the city of Buffalo, county 5 of Erie, and State of New York, have invented certain new and useful Improvements in Grab-Buckets, of which the following is a full, clear, and exact description.

My invention relates generally to grab 10 buckets and more particularly to means for holding the segments of the bucket open when the same are lowered upon the material being handled.

The principal object of my invention has 15 been to provide a holding means which would be simple in its construction, of few parts, and cheap to manufacture.

Another object has been to provide a device which shall be entirely automatic in 20 its operation and one which requires no additional lines or manually operated devices for its actuation.

Furthermore, my device is of such a compact design that it has no parts projecting 25 beyond the bucket to strike the hatchways of a vessel when unloading the same.

The above objects and advantages have been accomplished by the device shown in the accompanying drawings, of which:

30 Figure 1 is a side elevation of a single line bucket provided with my holding means.

Fig. 2 is an end elevation of the same.

Fig. 3 is an enlarged view of a portion 35 of the holding means.

Fig. 4 is a sectional view taken on line 4-4 of Fig. 3.

Figs. 5 to 11, inclusive, show modified 40 forms of latching devices for the holding means.

Referring to the drawings, and more particularly to Figs. 1 to 4, inclusive, 15 and 16 are the bucket segments, each being provided with a trunnion plate 17 and 18, respectively, at each side thereof. These trunnion plates are pivotally mounted on the trunnion pins 19 carried by the lower sheave block casing 20. The outer ends of the bucket segments are carried by means of 50 the links 21 which are pivotally secured at their lower ends to the corners of the bucket segments and at their upper ends to a central pivot pin 22 carried by the head 23.

55 Fig. 24 is the single line which passes around the sheaves of the head 23 and the lower sheave block casing 20, and to the bucket

lifting and operating mechanism. As is well known, a suitable hook (not shown) is provided, whereby the head 23 is connected and disconnected with any of the usual overhead suspending means. These means do not form a part of the present invention, and, therefore, are not shown or described. Equalizer links 25 are provided at each side of the bucket and connect the 60 trunnion plates 17 and 18, whereby the bucket segments are given equal velocities of rotation about their trunnion pins, where the bucket is opened or closed.

A latch bar 26 is pivoted at one end near 70 the outer edge of the bucket segment 16. 27 is a keeper bar, which preferably comprises two members 28 and 29 arranged adjacent each other in interspaced relation. One end of this keeper bar is pivotally connected near the outer edge of the segment 15. The free end of the latch bar 26 is arranged in the space between the members 28 and 29 of the keeper bar 27, and has a shoulder 30 formed near its free end. At 80 each side of the extreme end of this latch bar is provided a laterally projecting lug 31, which is arranged to slide upon the upper surfaces of the members 28 and 29 of the keeper bar. The keeper bar is provided at its free end with a separator 32, which is arranged between the members 28 and 29 thereof and slides on top of the latch bar 26. By this arrangement, when the bucket is fully open, as shown in dotted 90 lines in Fig. 1, these two bars lie in almost parallel, horizontal planes. So as to prevent the further opening of the buckets, the end 45 of the keeper bar is formed at substantially right angles with its bottom face 95 and is arranged to bear against stop plates 33, preferably forming the pivoted end of the latch bar 26.

Near the pivoted end of the keeper bar is arranged the latch mechanism of my device. 100 A U-shaped casing 34 is arranged about the members 28 and 29 with the open side of the casing disposed upwardly. This casing acts as a stop for the mechanism and also protects the same. Arranged in the space 105 between the members 28 and 29 of the keeper bar is the latch 35 of my device. This latch is pivoted at 36 to the members 28 and 29, the pivot being at the end of the latch nearest the center of the bucket. A 110 lateral flange 37 is provided at each side of the latch, so that only a predetermined

amount of upward travel of the latch is permitted by the engagement of these flanges with the under edges of the members 28 and 29 of the keeper bar. At the 5 end of the latch, opposite its pivotal connection, is provided a shoulder 38, which is engageable with the shoulder 30 of the latch bar when the latch is in its elevated position. Pivottally arranged within the 10 U-shaped casing 34 is a trigger 39, which is provided with a catch 40 and with a weighted arm 41. The catch 40 is engageable with a hook 42, formed on the latch 35 and disposed preferably beneath the shoulder 38 thereof. 15 43 is a pivot bracket for the keeper bar, which is rigidly secured to the bucket segment 15 and rotatable therewith. This bracket is disposed between the members 28 and 29 of the 20 keeper bar and is formed with a cam 44 engageable with the weighted arm 41 of the trigger, when the parts are in the position shown in Fig. 3 and the bucket is being closed.

25 When the bucket is being opened, the free ends of the latch bar and the keeper bar will be forced away from each other; and the free end of the latch bar will approach and move over the top of the latch 35 (in 30 its elevated position) until the motion is stopped by the engagement of the end 45 of the keeper bar with the stop plates 33 of the latch bar. When in this position, the shoulder 30 of the latch bar will have passed the 35 shoulder 38 of the latch, and the shoulder 30 of the bar will have fallen in front of the shoulder 38 of the latch. When the line 24 is taken up, the shoulder 30 of the latch bar will be drawn into engagement with the shoulder 38 of the latch, (dotted line position of Fig. 1) and the engagement of these shoulders will prevent the bucket from closing. As the shoulder 38 of the latch is above the pivotal 40 point thereof, the pull of the latch bar 26 will rotate the latch upon its pivot until its flanges 37 engage with the under side of the keeper bar 27. When the latch is elevated, it will release the engagement of the catch 45 40 of the trigger 39 with the hook 42 of the latch, and permit the trigger to fall to the position shown in Fig. 3. When the bucket is open, the cam 44 will have rotated to the position shown in this figure, in 50 which position it will permit the trigger to fall when released. When the parts are in the position above described, the bucket may be raised or lowered at will in its open position, and it will remain open, suspended by the line 24, until the tension on the line is released by lowering the bucket upon the lips of its segments. When so lowered, the segments will open slightly, thus releasing the engagement of the shoulders 30 and 38, and permitting the latch 55

to drop to the position shown in Fig. 3. In this position, the shoulder 38 of the latch will be below the upper edge of the members 28 and 29 of the keeper bar, and permit the free end of the latch bar to move 70 over these edges without engagement with the latch, thus permitting the bucket to be closed.

When the line 24 is drawn up and the bucket closed, the free ends of the latch bar 75 and keeper bar will be drawn toward each other; and, as the bucket segment 15 rotates, the cam 44 will contact with the weighted arm 41 of the trigger 39 and rotate it upon its pivot. When the bucket 80 segments are partly closed, the trigger will have been moved to the closed position of the bucket and its parts as shown in Fig. 1. During this movement, the trigger will raise the latch and the catch 40 will engage 85 with the hook 42 of the latch 35, and the latch thereby held in its elevated position and near to the end of its maximum upward movement. In this position of the latch, its shoulder 38 will project above the 90 upper surfaces of the members 28 and 29 of the keeper bar and be in a position to again engage with the shoulder 30 of the latch bar, when the bucket is again opened and raised.

95 Fig. 5 shows a fragmentary view of a modified form of latch means, and Fig. 6 shows a view of the same means in a different position. Fig. 5 shows the parts in the position they occupy when the bucket is 100 closed, and Fig. 6 shows, in full lines, the position of the parts when the bucket is being held open and suspended from the line 24. The positions occupied by the parts when the segments are ready to be closed 105 are shown by the dotted lines in Fig. 6.

In this form of device, 50 is the free end of the latch bar, and 51 the pivoted end of the keeper bar, only one member thereof being shown. The latch bar in this form is 110 also provided with lateral lugs 52 and with a shoulder 53. 54 is the latch which is pivotally mounted between the members of the keeper bar, and it is provided at its free end with a shoulder 55 which is engageable 115 with the shoulder 53 of the latch bar. Lateral flanges 68, engageable with the under side of the keeper bar, are also provided on the latch. The trigger 56 in this modification is in the form of a bell-crank lever, 120 having an outwardly extending arm 57 and a downwardly extending arm 58. It is pivoted at 59, within a recess 60 cut into the free end of the latch. A shoulder 61 is provided for limiting the upward travel of the trigger, and a shoulder 62 for limiting the downward travel of the trigger. Arranged about the members of the keeper bar at the point where the trigger is located, is a U-shaped casing 63, which has its bottom wall 125 130

64 arranged at an angle with the edges of the keeper bar. A stop 65 is arranged at one end of the casing and is provided with a shoulder 66 which is engageable with the 5 end of the trigger arm 58. 67 is the cam, which is rotatable with the bucket segment.

When the parts are as shown in Fig. 5 and the bucket segments are being opened, it will be seen that the weight of the latch 54 will 10 keep the arm 57 of the trigger 56 against the cam 67, so that the arm 58 of the trigger will come into engagement with the surface 66 of the stop 65. When these surfaces are in engagement, they will keep the parts in 15 the position shown in Fig. 6, (full lines) until the trigger is released from the surface 66. As the bucket segments continue to open, the latch bar 50 will move toward and along the top edge of the latch 54 until 20 its shoulder 53 has passed the shoulder 55 of the latch. When the line 24 is taken up, the shoulders 53 and 55 will come into engagement and the pull on the latch bar 50 will slightly raise the free end of the latch 25 54 until its flanges 68 engage with the under side of the keeper bar 51. This movement will release the end 58 of the trigger from engagement with the surface 66 of the stop and allow the trigger to drop against the 30 stop 62. When the trigger is in this position, and the pull of the latch bar 50 is released, the latch 54 and trigger will fall into the position shown in dotted lines (Fig. 6). When the bucket segments are being closed, 35 the latch bar will pass over the top of the latch without engaging therewith, and the cam 67 will engage with the trigger arm 57 and move the arm 68 thereof against the side of the stop 65. Continued rotation of the 40 cam, in closing the bucket, will move the latch 54 and the trigger to the position where the arm 58 will clear the upper edge of the stop 66, at which time it will be free to swing to the position shown in Fig. 5, 45 where the arm 57 thereof will bear against the stop 61.

In Fig. 7 of the drawings, the parts of the modification there shown are in the positions they occupy when the bucket segments are 50 closed. In Fig. 8, the full lines show the positions occupied by the parts when the bucket is being held open and suspended from the line 24. The dotted lines of this figure show the positions of the parts when 55 the latch is released. 70 is the latch bar, having lateral lugs 71 and a shoulder 72. 73 is the keeper bar (only one member thereof being shown). 74 is the latch and 75 is the trigger, each pivotally mounted between the members of the keeper bar. Arranged between the latch and the trigger is a keeper 76, also pivotally attached to the keeper bar. The latch in this form is provided on its free end with a projection 77, 60 the upper surface of which lies some dis-

tance below the shoulder 78 thereof. The keeper is provided with a weighted arm 79 projecting toward the latch and provided with a projecting shoulder 80, which is engageable with the projection 77 of the latch. 70 Lateral flanges 81 are provided for limiting the upward motion of this weighted arm of the keeper. An outwardly and downwardly extending arm 82 is provided on the keeper at the opposite side of its pivotal point and 75 this arm is engageable with the end surface 88 of an arm 83 provided on the trigger. The trigger is provided also with a cam arm 84, and its pivot is so disposed as to make this last mentioned arm of the trigger 80 heavier than the opposite arm. 85 is the cam which is secured to and rotatable with one of the bucket segments. A U-shaped casing 86 is provided for inclosing these parts. A stop 87 is carried by the casing 85 for limiting the downward motion of the latch 74.

When the bucket segments are being opened, the keeper 76 will retain the trigger 75 in the position shown in Fig. 7, even 90 though the cam moves away from the arm 84 thereof. When the segments are open, the weighted arm 79 of the keeper lies below the upper surface of the keeper bar, so that as the shoulder 72 of the latch bar 70 95 passes the shoulder 78 of the latch, it will fall in between the members of the keeper bar and be in such a position that when the line 24 is taken up, the shoulders 72 and 78 will engage. When so engaged, the latch 100 will be raised to the position shown in Fig. 8; and, as its projection 77 is in engagement with the shoulder 80 of the keeper, the keeper will also be raised until its flanges 81 engage with the lower edges of the keeper bar. When in this position, a further upward movement of the latch or keeper is thus 105 prevented. When the keeper is moved to the position just described, or that shown in Fig. 8, it will be seen that the arm 82 will 110 have moved out of engagement with the arm 83 of the trigger, thus allowing the heavier end 84 of the trigger to fall to the position in Fig. 8. When the pull of the latch arm 70 is now released, the latch 74 115 will fall to the dotted line position of Fig. 8. It will be seen, however, that the surface 88 of the arm 83 will engage with the arm 82 of the keeper and thus maintain its weighted arm 79 in the position shown. 120 When the keeper is in this position, the free end of the latch bar will slide along its upper surface and thus be prevented from dropping down between the members of the keeper bar and again engaging with the 125 shoulder 78 of the latch. When the bucket segments are being closed, the cam 85 will again restore the trigger to a position where the arm 82 of the keeper can move over the top of the arm 83 of the trigger as shown 130

in Fig. 7, and thus reset the parts for reengagement with the latch bar.

In the form of device shown in Figs. 9, 10, and 11, 90 is the latch arm having a shoulder 91 and lateral lugs 92, and 108 is the keeper bar. 93 is the trigger which is provided with a weighted arm 94, engageable with the cam 95. The opposite end 96 of the trigger is provided with a surface 97 and a shoulder 98. 99 is the latch, which is bell-crank in form, having an upwardly extending latch arm 100, providing a shoulder 106, and an outwardly extending arm 101. A stud 102, having a head 103, is slidably arranged in the arm 101 of the latch. Between the head of the stud and the latch is a helical spring 104, and an adjusting nut 105 is provided for the threaded end of the stud, whereby the relative height 20 of the head 103 may be adjusted. A U-shaped casing 107 is also provided for this form of my invention.

In Fig. 9, the parts are shown in the positions which they occupy when the bucket 25 is opened. It will be noted from this figure, that the weighted arm 94 of the trigger is not in contact with the cam 95. When the line 24 is taken up, the shoulder 91 of the latch arm will engage with the shoulder 30 106 of the latch and rotate the same about its pivot. During this rotation, the head 103 of the stud being in contact with the under side of the latch arm, the spring 104 will be compressed, as shown in Fig. 10. 35 The surface of the shoulders 91 and 106 are so proportioned that the coefficient of friction between them is such that the surfaces will remain engaged against the force of 40 the spring which has a tendency to separate them. When the spring is fully compressed and the latch has moved to its maximum upward position, its end 101 will have moved over the surface 97 of the trigger, and when the end 101 moves past the shoulder 45 98, the trigger will be rotated upon its pivot by gravity and will occupy the position shown in Fig. 10, with the shoulder 98 beneath the end 101 of the latch. When 50 the bucket is lowered, and the pull of the latch bar 90 is released, the frictional engagement of the shoulders 91 and 106 will also be released. The spring 104 will then expand and raise the free end of the latch bar to the position shown in dotted lines in 55 Fig. 10, where the shoulder 91 will pass over the shoulder 106 without engagement therewith, when the bucket is closed. As the bucket is closing, the cam 95 will rotate the trigger 93 until its shoulder 98 has moved 60 out of engagement with the end 101 of the latch. This will release the latch and permit it to fall to its lowermost position, as shown in Figs. 9 and 11, in which position it will again engage with the shoulder of

the latch bar when the bucket is opened 65 and the line 24 tightened up.

While I have described my holding means applied to the type of bucket shown in the drawings, it may be used with any type of 70 grab bucket or clam-shell bucket, irrespective of the opening and closing means provided on such bucket.

It will be understood that the latch bar, keeper bar, and the latch device form the 75 essential elements of my invention, and in the drawings I have shown but a few of the many possible forms of latch device. It is 80 obvious that many modifications of the details herein shown and described may be made, and many other forms of latching device may be used without departing from the spirit of my invention or the scope of the appended claims; and, therefore, I do not wish to be limited to the exact embodiment herein shown and described. 85

Having thus described my invention, what I claim is:

1. In a grab bucket, the combination, with bucket segments, of means for preventing the bucket segments from being opened beyond a predetermined point, and means for locking the segments while in their open position, said means being confined within the outlines of the bucket itself. 90

2. In a grab bucket, the combination, with bucket segments, of means for preventing the bucket segments from being opened beyond a predetermined point, and means for locking and unlocking the segments while in their open position, said means being confined within the outlines of the bucket 95 itself. 100

3. In a grab bucket, the combination, with bucket segments, of holding means comprising a latch bar pivoted near the outer end 105 of one of the bucket segments, and a keeper bar pivoted near the outer end of the opposite segment, the free ends of said bars being slidably engaged, and means carried by the bars for locking the segments in their 110 open position.

4. In a grab bucket, the combination, with bucket segments, of a bracket secured to one of the bucket segments, a latch bar pivotally secured to the bracket, stops carried by the 115 latch bar, a keeper bar pivoted to the opposite segment and having its free end engageable with the stops of the latch bar for preventing the bucket from opening beyond a predetermined point, and means for locking 120 the segments in their open position.

5. In a grab bucket, the combination, with bucket segments, of holding means comprising a latch bar pivoted near the outer end 125 of one of the bucket segments, and a keeper bar pivoted near the outer end of the opposite segment, the free ends of said bars being slidably engaged, means carried

- by the bars for locking the segments in their open position, and a cam rotatable by one of the segments for resetting the holding means.
- 5 6. In a grab bucket, the combination, with bucket segments, of holding means comprising a latch bar pivoted near the outer end of one of the bucket segments and provided with a shoulder and a keeper bar pivoted near the outer end of the opposite segment, the free ends of said bars being slidably engaged, and means carried by the bars for locking the segments in their open position, comprising a latch provided with a shoulder 10 for engagement with the shoulder of the latch bar, when the parts are in their locked position, means for allowing the latch to fall to its inoperative position, and means for resetting the latch.
- 15 7. In a grab bucket, the combination, with bucket segments, of holding means comprising a latch bar pivoted near the outer end of one of the bucket segments, and a keeper bar pivoted near the outer end of the opposite segment, the free ends of said bars being slidably engaged, means carried by the bars for locking the segments in their open position, comprising a latch engageable 20 with the latch bar and a trigger engageable with the latch, and a cam rotatable by one of the segments and engageable with the trigger for resetting the latch.
- 25 8. In a grab bucket, the combination, with bucket segments, of holding means comprising a latch bar pivoted near the outer end of one of the bucket segments and provided with a shoulder and a keeper bar pivoted near the outer end of the opposite segment, the free ends of said bars being slidably engaged, and means carried by the bars for locking the segments in their open position, comprising a trigger provided with a catch, a latch provided with a hook for engagement with the catch of the trigger, the latch being also provided with a shoulder engageable 30 with the shoulder of the latch bar, and means for resetting the latch.

ing a latch bar pivoted near the outer end 35 of one of the bucket segments and provided with a shoulder, and a keeper bar pivoted near the outer end of the opposite segment, the free ends of said bars being slidably engaged, and means carried by the bars for 40 locking the segments in their open position, comprising a trigger provided with a catch, a latch provided with a hook for engagement with the catch of the trigger, the latch being also provided with a shoulder engageable 45 with the shoulder of the latch bar, and means for resetting the latch.

9. In a grab bucket, the combination, with bucket segments, of holding means comprising a latch bar pivoted near the outer end 50 of one of the bucket segments and provided with a shoulder, and a keeper bar pivoted near the outer end of the opposite segment, the free ends of said bars being slidably engaged, and means carried by the bars for 55 locking the segments in their open position, comprising a trigger provided with a catch, a latch provided with a hook for engagement with the catch of the trigger and being also provided with a shoulder engageable 60 with the shoulder of the latch bar, the latch being also provided with lateral flanges engageable with the under side of the keeper bar when the bucket is held open by the holding means.

In testimony whereof I have hereunto signed my name.

FRANK H. WILLIAMS.
